UNITED STATES PATENT OFFICE

LUCIEN LEVY, OF PARIS, FRANCE

LOUD-SPEAKER

Application filed October 1, 1928, Serial No. 309,425, and in France October 4, 1927.

My invention relates to improvements in loud-speakers. Instruments so-called loud-speakers have already been proposed for converting electric energy having an audible frequency into audible energy and inversely. Said instruments comprise essentially an electric motor which converts alternate electric energy into oscillatory mechanical energy and a diaphragm designed to receive at certain points of its surface the oscillatory mechanical energy which propagates on the surface of the diaphragm and is transmitted in part to the air particles in contact with the diaphragm.

In loud speakers the diaphragm is frequently made of metal and is of reduced dimensions, but it is frequently embedded and capable of vibrating itself. On the other hand the sound horn is capable of sounding under the action of certain acoustic vibrations. The result of the above phenomena is that the loud speaker has an efficiency

$$\rho = \frac{\text{acoustic energy emitted}}{\text{electric energy supplied}}$$

which varies with the frequency thus altering the reproduction of the voice.

In diffusers the diaphragm which sends forth acoustic energy is of large dimensions but as the mechanical energy is produced at one point only there are produced on the surface of the diaphragm phenomena of elastic wave propagation which also create especially for certain frequencies stationary wave phenomena having for result a varying output of the coefficient and an alteration of the voice.

It will also be noted that at a given moment, owing to the propagation of the elastic wave, the various parts of the diaphragm acquire different speeds which may even be of opposite direction at points located at various distances from the center of commotion; consequently one part of the diaphragm radiates in an opposite direction to that of another part thus creating currents of acoustic circulation which possess no radiating energy and produce losses of energy.

Lastly at certain points of the diaphragm the vibratory energy is of such a nature that

it may be integrally radiated in the surrounding atmosphere, said points are those at which the vibratory energy of the diaphragm per cm^2 for a given amplitude V_0 is equal to the vibratory energy that the surrounding air may carry (given for instance by Wien's formula)

$$W \text{ (watts)} = 1.190 \times 10^{10} \left\{ \frac{C}{V} \frac{U_0}{c} \right\} \quad 60$$

$$= 1.190 \times 10^{10} \left\{ \frac{C 4 \pi 2 \rho^2 V^2}{c V^2} \right\} \quad 65$$

V — speed of sound
 U_0 — amplitude
 C — specific heat at constant pressure and constant volume

Briefly stated, the emission of energy by means of a diffuser is a complex phenomenon which baffles all reliable calculations, which produces great losses of energy, it requires in fact much larger surfaces than those which would be necessary if all parts of the radiating surface were rationally utilized and which owing to the non-radiation of the whole energy existing at every point produces resonance phenomena.

My invention relates to improvements in acoustic radiating surfaces with the object of producing:

1st, a good radiating energy per cm^2 of the surface.

2nd, a continuous radiation at all frequencies.

3rd, the absence of all resonance phenomena.

According to my invention instead of utilizing the radiating diaphragm as wave transmitting surface (this being the case when vibratory mechanical energy is applied at one point of said diaphragm) it is specialized in its radiating function: 1st by the application of mechanical energy at numerous points vibrating in phase or approximately; 2nd by equalizing the vibratory energy applied to the diaphragm for a given frequency and amplitude to the energy which it can radiate for the same amplitude at the same frequency.

- quency; showing thus that when this uniformity is obtained for a given frequency it is obtained for all frequencies provided that the 1st condition is fulfilled; the uniformity is obtained by providing the motor with a lever device the ratio of which may be regulated in order to act upon the transmitter; 3rd by interposing between the motor which delivers the vibratory energy and the radiating diaphragm one or more surfaces for the propagation of elastic waves designed to connect the motor with the various points of the diaphragm by giving them motions which are substantially in phase.
- 10 The diaphragm may be made of any appropriate light substance which does not propagate the elastic waves, such as rubber, gold-beater's skin, material, cellulose acetate, paper, etc.
- 15

- 20 The waves propagating surface should be such that the propagation speed will be as high as possible in order that the phase displacement may be as slight as possible between the various points of the diaphragm.
- 25 Consequently it will be made preferably of metal such as duralumin when the propagation speed is about 5000 meters per second.

Thus in the case of 5000 periods the wave length is approximately 1 meter and in that 30 of a loud speaker having a radius of about 25cm the phase displacement between two points on the diaphragm is less than $\frac{1}{4}$ period and may be moreover reduced at will.

The invention will be better understood by 35 reference to the accompanying drawing in which Fig. 1 represents a loud speaker diaphragm constructed according to my invention.

- 40 Referring to the drawing, Fig. 1 designates the motor operating the wave propagating surface which is composed of a series of triangular shaped metal blades 2 soldered together provided with a circular foot 3, Figs. 2 and 3, forming together equal dihedrons.
- 45 Fig. 2 is a rear view of the diaphragm; Fig. 3 shows a single blade for connecting the motor to the diaphragm.

A radiating diaphragm 4 of material, rubber, paper, etc., in the shape of a spherical 50 cap is stretched over the feet 3. It is preferably contained in a casing 5 to which it is connected by means of an elastic joint 6 which prevents the circulating currents passing between the front and the back surface of the 55 radiating diaphragm 4.

The feet 3 of the blades may be connected together by means of a wire netting 8.

The mode of operation is as follows:

- 50 The mechanical vibrations produced by the motor are transmitted to the blades at the point 7. They produce elastic waves in said blades which transmit synchronous motions to every point of the feet 3 and consequently to every point of the diaphragm.

- 65 All the improvements as above described

may apply indifferently to the operation with a loud speaker or with a receiving microphone.

What I claim and desire to secure by Letters Patent of the United States is:

1. In a loud speaker, a radiating membrane that does not propagate waves, and a wave propagating surface connected to the rear of the membrane along lines whose points vibrate in phase.

2. In a loud speaker, a radiating membrane that does not propagate waves and having spherical form, and a propagating surface of radial orthogonal blades symmetrically disposed about the axis of the membrane, the lines of contact of the blades with the membrane being along curves all of whose points vibrate in phase.

3. In a loud speaker, a spherical paper membrane, and a wave propagating means connected thereto, said means consisting of radial metallic vanes connected orthogonally to the membrane and regularly disposed about its axis and having curved lines of contact with the membrane all of whose points vibrate in phase.

In testimony that I claim the foregoing as my invention I have signed my name.

LUCIEN LEVY.
